UNITED STATES PATENT OFFICE.

BAYARD E. TAYLOR, OF OAK PARK, ILLINOIS.

AUTOMOBILE DOOR LOCK.

1,417,423.

Specification of Letters Patent. Patented May 23, 1922.

Application filed June 21, 1920. Serial No. 390,342.

To all whom it may concern:

Be it known that I, BAYARD E. TAYLOR, a citizen of the United States, and a resident of the village of Oak Park, in the 5 county of Cook and State of Illinois, have invented certain new and useful Improvements in an Automobile Door Lock; and I do hereby declare that the following is a full, clear, and exact description of the 10 same, reference being had to the accompanying drawings, and to the numerals of reference marked thereon, which form a part of this specification.

In the building of closed automobile 15 bodies the thickness of the doors is governed by the vertically adjustable sashes and the thickness of the door locks. In order that the thickness of the doors may be reduced to a minimum, efforts have been exerted to 20 produce an automobile door lock wherein the operating parts are so related that the thickness of the lock is reduced to a minimum consistent with strength and wearing qualities of the operating parts.

25 This invention pertains to an improved type of a vehicle door lock of slight depth or thickness and wherein the locking bolt and an associated wedge member are adapted to be operated by pivoted levers against the 30 action of controlling springs to permit opening of the door from either the exterior or interior of the automobile.

It is an object of this invention to provide 35 an automobile door lock of simplified construction and of minimum thickness, and adapted to be locked or unlocked from both sides of the door to permit retraction of the locking bolt and its wedge member by the operation of either an outer handle or an 40 inner handle.

It is also an object of the invention to construct a door lock of comparatively slight depth wherein the latching members may be retracted from the inner side of a door by 45 means of a handle adapted to be rotated in a direction which will simultaneously retract the latching members and swing the door outwardly into open position with one operation.

50 Another object of the invention is to provide a striking plate with an inturned flange

to provide an increased bearing surface for the wedge bolt.

It is a further object of this invention to provide a vehicle door lock with a means 55 for securing the latching members in extended position by turning a thumb piece in a direction ordinarily used to move a bolt into latching position.

It is furthermore an object of the invention to provide a thin door lock wherein a locking bolt and its associated wedge member are adapted to be normally moved and held in their projected positions by means of a spring controlled lever pivoted on the 60 wedge member and engaging the locking bolt.

It is an important object of this invention to provide a thin door lock requiring 65 but a very shallow recess in the door to receive the same and having a locking cam adapted to be moved into a locking or unlocking position from the inner side of the door by means of a thumb handle or from the exterior of the door by means of a key 70 actuated pin lock.

Other and further important objects of this invention will be apparent from the disclosures in the specification and drawings.

The invention (in a preferred form) is 80 illustrated in the drawings and hereinafter more fully described.

On the drawings:

Figure 1 is a front elevation of a door lock embodying the principles of this invention and showing the handle for operating the lock mechanisms from the inner side of the door.

Figure 2 is a fragmentary top plan view 90 of the door.

Figure 3 is an enlarged fragmentary detail section taken on line 3-3 of Figure 2.

Figure 4 is an enlarged section taken on line 4-4 of Figure 1 with parts shown in elevation.

Figure 5 is an enlarged detail front elevation of the lock with the cover and wedge member removed.

Figure 6 is an enlarged detail front elevation of the lock with the cover removed 100 and with the locking bolt and wedge in projected latching position.

Figure 7 is a reduced section taken on line 7—7 of Figure 6 and showing the cover in position.

Figure 8 is an enlarged detail section 5 taken on line 8—8 of Figure 1.

Figure 9 is an enlarged detail section taken on line 9—9 of Figure 1.

Figure 10 is a fragmentary detail section taken on line 10—10 of Figure 6.

10 Figure 11 is a fragmentary detail section taken on line 11—11 of Figure 6.

Figure 12 is an elevational view of a modified form of door lock with the cover removed.

15 Figure 13 is an end view thereof with the cover in place.

Figure 14 is a section taken on line 14—14 of Figure 12.

20 Figure 15 is a detail sectional view taken on line 15—15 of Figure 14.

Figure 16 is an elevational view of the modified lock with the cover, wedge mechanism and the lever handle removed.

As shown on the drawings:

25 The reference numeral 1 indicates a vehicle door and 2 the door frame having a recess 3 therein. Rigidly secured to the door frame 2 is a strike plate 4 provided with an opening 5, which registers with the 30 door frame recess 3. Integrally formed on the strike plate 4 is a slightly inclined flange 6 which projects into the recess and affords an increased bearing surface for a wedge bolt hereinafter described.

35 The inner side of the door 1 is provided with a comparatively shallow recess for receiving the relatively thin door lock embodying the principles of this invention. The lock illustrated in Figures 1 to 11 in-

40 clusive, comprises a mounting plate or back plate 7, one end of which is bent forwardly at an angle to afford a flange 8 having an opening therein to permit the lock latching members to project therethrough. Secured

45 in a stud or boss 9 struck from the back plate 7 is the inner end of a coiled spring 10, the outer end of which projects upwardly and engages against a lug 11 integrally formed on a pivoted lever or arm 12. The lower end of the lever 12 is pivoted on a pin 13 integrally formed on one

50 side of the inner end of a slidable bar 14. Integrally formed on the opposite side of the slidable bar 14 is a guide block or lug 15 which projects into and is slidable in a horizontal guide slot 16 formed in a cover or casing 17 secured to the back plate 7 to enclose the operating mechanisms of the lock. The rearward movement of the slide

55 60 bar 14 is limited by the lug 15 striking the casing at the end of the guide slot 16. The slide bar 14 is deflected at 18 and has rigidly secured on the end thereof a wedge 19, which is slidable through the opening in

65 the flange 8 and is furthermore adapted

by rearward movement of the slide bar 14 to move in a channel strap or saddle 20 secured on the outer surface of the back plate 7 to afford a guide for the latching members of the lock. The saddle 20 projects outwardly from the back plate through an opening 21 in the casing 17. The casing opening 21 permits retraction of the wedge 19.

The wedge slide bar 14 is cut away at 75 the sides thereof to afford shoulders adapted to contact the inner ends of flanges 22 integrally formed on opposite margins of a slidable latch bolt 23. Integrally formed on the inner end of the latch bolt 23 is an 80 upwardly directed arm 24, to the upper deflected end of which is integrally connected two parallel arms 25 and 26. The arm 25 is uppermost and has the ends thereof bent toward the back plate 7 to afford lugs or 85 flanges 27 and 28. The arm 26 is deflected at 29 to permit the same to form a guide member slidable in a longitudinal slot 30 provided in the casing 17. The inner end of the arm 26 is bent toward the back plate 90 7 to form a lug or flange 31. As shown in Figure 5, the upper end of the lever 12 contacts the flange 28 of the upper arm 25 to hold the latch bolt in projected position. To retract the latch bolt 23 to permit opening 95 of the door from the exterior of a vehicle, an outer door handle 32 is provided having a stem 33 the inner squared end of which projects into a squared opening formed in one end of a dog or roll back 100 34 supported between the back plate 7 and the casing 17. The free end of the roll back 34 is in contact with the flange 27 of the upper arm 25 of the latch bolt, so that when the outer handle 32 is turned the roll back 105 34 forces the latch bolt 23 inwardly together with the wedge 19 since the shoulders of the wedge bar 14 are in contact with the latch bolt flanges 22.

For the purpose of opening the door from 110 the interior of the vehicle, a second or inner handle 35 is provided on the top of the door. A vertical stem or shaft 36 is secured to the handle 35 and projects downwardly into the door to permit the flattened end thereof to 115 have a cam 37 rigidly secured thereon. The cam 37 is supported in a bracket 38 secured to the back plate 7 and around the upper cylindrical portion of the cam. The cam 37 is in contact with a lug 39 integrally formed 120 on one margin of a hanging lever or arm 40. The upper end of the arm 40 is pivotally mounted on the back plate 7 while the lower end of said arm 40 is disposed against the flange 31 and between the back plate 7 125 and the latch bolt arm 26.

A locking device is provided to permit the latch bolt 23 to be locked in its projected position to prevent opening of the door by actuation of either of the door handles 32 130

or 35. For this purpose a third handle or thumb turn 41 is provided on the inner side of the door. The thumb turn 41 has a squared stem 42, which projects through a squared opening in a collar 43 disposed between the casing 17 and the back plate 7. The end of the stem 42 is provided with a tenon 44 adapted to be removably engaged in a slot formed in a plug or projection 45 secured to the barrel of a pin lock 46. The lock 46 is mounted in the door 1 and is adapted to be unlocked from the exterior of the door by means of a key. To permit the thumb turn 41 to be operated from the inner side of the door when the lock 46 is locked, the stem tenon 44 is pulled out of engagement with the projection 45. The stem 42 may then be turned by the thumb turn 41 to actuate the collar 43. A projection or lug 47 is formed on the collar 43 and is adapted to be engaged in a notch 48 provided in a dog or cam 49. The cam 49 is pivotally mounted on a pin 50 secured to the back plate 7. A pin 51 is also secured on the back plate 7 and has a spring 52 engaged therearound. The ends of the spring 52 cross each other to permit one end to contact the pin 50 and the other end to engage the edge of the cam 49 to coat with a rounded nub or tooth 53 formed on said cam. The cam 49 is provided with a notch 54 for the purpose of engaging the inner lower corner 55 of the latch bolt 23 when the latch bolt is in projected position and the cam 49 has been turned into locking engagement with the latch bolt, as shown in Figure 6.

In the modified form of the device illustrated in Figures 12 to 16 inclusive the door lock comprises a mounting or back plate 56, one end of which is bent at an angle to afford a flange 57 having an opening therein to permit the latching members to be projected therethrough. Secured in a stud 58 on the back plate 56 is the inner end of a coiled lower spring 59, the outer end of which projects upwardly and is engaged against a shoulder 60 of a slidably wedge bar 61. The outer end of the wedge bar 61 is deflected and has rigidly secured thereon a wedge 62, which projects through an opening provided in a casing or housing 63. The casing 63 is rigidly secured to the back plate 56 to enclose the operating mechanisms of the door lock. Secured to the back plate 56 is a saddle 64, which projects outwardly from the casing opening to afford a guide for the wedge 62. The spring 59 acts to hold the wedge 62 in its projected position.

Integrally formed on the sides of the slideable wedge bar 61 are guide flanges 65, which are directed toward the back plate 56 and slidably engage the side edges of a slideable latch bolt 66. The outer or latching end of the latch bolt 66 has integrally formed on the opposite margins thereof

flanges 67, between which the wedge 62 is slideable. The inner end of the latch bolt 66 is slideable between two guide flanges or lugs 68 struck from the back plate 56. A flange or lug 69 is integrally formed on the inner end of the latch bolt. Integrally formed on the upper margin of the latch bolt is a shoulder 70, against the inner end of which the outer end of a coiled upper spring 71 is engaged. The inner end of the spring 71 is connected to a stud 72, which is rigidly secured to or struck from the back plate 56. The spring 71 acts to normally hold the latch bolt 66 in its projected position.

To retract the latch bolt 66 from the exterior of a vehicle door, an outer handle is provided having a stem the inner squared end 73 of which projects into a squared opening formed in one end of a dog or roll back 74 supported between the back plate 56 and the casing 63. The free end of the roll back 74 is in contact with the front end of the latch bolt shoulder 70 so that when the outer handle is turned the roll back 74 will force the latch bolt 66 inwardly together with the wedge 62 since the inner ends of the wedge bolt flanges 67 are in contact with the slideable wedge bar 61.

For the purpose of retracting the latch bolt 66 from the inner side of a vehicle door an inner handle or lever 75 is provided. The lower end of the lever 75 is removably engaged on a pin 76 formed on a flexible strip 77 of the back plate 56 below a horizontal slot 78 cut in the lower portion of said back plate. The lower end of the lever 75 is provided with a series of apertures 79 to permit the pin 76 to be engaged in different of the lever apertures for the purpose of adjusting the lever. The lever 75 projects downwardly into the casing 63 in front of and in contact with the flange 69 of the latch bolt.

The operation is as follows:

In the form of door lock shown in Figures 1 to 11 inclusive the spring 10 pressing against the pivoted arm 12 acts to hold the latch bolt 23 and the wedge 19 in their projected positions as shown in Figures 6 and 8. With the door 1 in closed position the latch bolt fully engages in the strike plate opening 5 before movement of the wedge begins. The wedge 19 then follows and wedges against the inturned flange 6 of the strike plate 4, thereby permitting the latch bolt and the wedge to hold the door rigidly in place in the door frame to prevent rattling of the door. The wedge is slideable with respect to the latch bolt 23 and under the impulses of the spring 10 is shot or driven into the space between the flat surface of the latch bolt 23 and the flange 6 of the strike plate 4.

With the locking cam 49 in release position, as shown in Figure 5, the closed door 1 may be readily opened from the exterior of

the vehicle by turning the outer handle 32 thereby causing the roll back 34 to press against the flange 27 to force the latch bolt 23 inwardly against the action of the spring 10. The flanges 22 of the latch bolt being 5 in contact with the wedge bar 14, both the latch bolt and the wedge are simultaneously retracted as a unit and the door may be 10 swung into open position on its hinges. Release of the handle 32 permits the stressed 15 spring 10 to again force or shoot the latch bolt 23 and the wedge 19 outwardly through the opening in the back plate flange 8.

To open the door from the interior of the 15 vehicle the inner handle 35 is turned thereby causing the cam 37 to partially rotate. This operation of the cam 37 acts to force the pivoted arm 40 rearwardly. The rearward movement of the arm 40 serves to 20 retract the latch bolt 23 and the wedge 19 against the action of the spring 10. With the turning of the handle 35 and the retraction of the latch bolt and wedge the door is 25 swung outwardly into open position with the one operation of the handle. The wedge and latch bolt may be simultaneously retracted by either of the handles 32 or 35 independently of the other. The rearward movement of the latch bolt and the wedge is limited by 30 the stop block 15 which is slidable in the casing slot 16.

When it is desired to lock the latch bolt 23 and the wedge 19 against retraction to 35 prevent opening of the door by operation of the handles 32 and 35, a key is inserted into the pin lock 46 and the barrel of the lock is turned causing the lug 47 to engage in the notch 48 of the locking cam 49. The cam 49 is thus moved upwardly from the position 40 shown in Figure 5 into the locking position shown in Figure 6. The notch 54 of the cam 49 permits the cam to lockingly engage the corner 55 of the latch bolt 23. With the latch bolt 23 locked in position it will be 45 noted that the handles 32 and 35 cannot be operated to retract the latch bolt. To permit retraction of the latch bolt and wedge, the key must be inserted into the pin lock 46 so that the lock barrel may be rotated to 50 move the locking cam 49 back into release position. When the lock 46 is locked, the door 1 may be locked from the interior of the vehicle by first disengaging the tenon 44 from the lock projection 45 and then turning the 55 thumb turn 41 whereby the locking cam 49 is moved into locking engagement with the shoulder or corner 55 of the latch bolt 23. The tenon 44 is then again engaged in the lock projection 45. It will thus be seen that 60 all the doors of a closed vehicle except one may be locked from the inside of the vehicle by means of the thumb turns or handles 41, the last door permitting a person to leave the car to lock the last door by means of a 65 key from the exterior of the vehicle. All

of the doors may be unlocked by keys from the exterior of the vehicle when the thumb turns interfit the lock projections 45 or by means of the thumb turns 41 from the interior of the vehicle when said thumb turns 70 are disengaged from the lock projections.

In the modified form of door lock illustrated in Figures 12 to 16 inclusive, the operation is similar to that already described. The latch bolt 66 and the wedge 62 are held 75 in their projected positions by the respective springs 71 and 59. The latch bolt and wedge may be retracted from the exterior of a vehicle by actuating the roll back 74 by the outer handle of the door. To retract the 80 latch bolt 66 and the wedge 62 from the interior of the vehicle the lever 75 is swung rearwardly, thereby engaging the latch bolt lug 69 causing the latch bolt and the wedge to slide inwardly against the action of the 85 springs 59 and 72. Release of either of the door handles permits the springs 59 and 72 to shoot the latch bolt and wedge outwardly into their normal projected positions.

The latch bolt and the wedge are mounted 90 to permit the same to move together when the door is opened but differentially with respect to each other when the door is closed so that the wedge follows and moves on the latch bolt to engage between said latch bolt 95 and the flange 6 of the strike plate 4, to take up any play, thereby preventing rattling of the door when in closed position.

Attention is directed to the novel means whereby the lever 78 may be removably 100 mounted in position so that the length of the lever extending above the top of the door may be changed to suit the various types of doors used on cars of different make. To mount the lever 75 the apertured end 105 thereof is projected into the casing 63. The portion 77 of the back plate 56 is then sprung outwardly to permit the pin 76 to engage in any one of the lever apertures 79 in register with said pin when the plate portion 77 is 110 released and bent back into the plane of the back plate 56. The lever 75 may be removed if not required.

The various parts of the door lock are 115 mostly constructed by punching them out of sheet metal, thereby obviating most of the machining, and the few parts made by die casting of course require but little if any machining.

I am aware that numerous details of construction may be varied through a wide range without departing from the principles of this invention, and I therefore do not purpose limiting the patent granted otherwise than necessitated by the prior art. 120

I claim as my invention:

1. A door lock comprising a latch bolt, a wedge member, an arm pivotally mounted on said wedge member and engaging said latch bolt, resilient means engaging said 130

arm for first impelling said latch bolt and then the wedge member outwardly into latching position, and handle mechanisms operable independently of each other for reTRACTING the latch bolt and wedge member against the action of said resilient means.

2. A door lock comprising a latch bolt, a wedge member associated therewith, an arm pivoted on said wedge member and engaging said latch bolt, control means engaging said arm for impelling said latch bolt and then the wedge member outwardly into latching position, handles operable independently of each other for retracting the latch bolt and the wedge member against the action of said control means, and means for locking the latch bolt and the wedge member against retraction by said handles.

3. A lock comprising a slidable latch, a wedge member slidably engaged therewith, an arm pivoted on said wedge member and contacting said latch, and a spring engaging said arm to move the latch and then the wedge member into latching position.

25 4. A lock comprising a slidable latch, a wedge member slidably engaged therewith, an arm pivoted on said wedge member and contacting said latch, a spring engaging said pivoted arm for holding the latch and the wedge members in projected latching position, means for retracting said latch and said wedge member against the action of said

spring, and a locking mechanism adapted to be moved into engagement with said latch to hold the latch and the wedge member locked in their projected positions against retraction by said means.

5. In a door lock the combination with a latch, of a member integrally formed thereon, flanges on opposite ends of said member, a pivoted arm, a spring mechanism engaged with said pivoted arm to cause the same to press against one of said flanges to hold the latch in projected latching position, a roll back engaged with the other flange of said member, and a handle connected with said roll back and adapted to be actuated to cause said roll back to retract the latch against the action of said spring mechanism.

6. A lock comprising a slidable latch, a wedge mechanism slidably engaged therewith, and resilient means associated with the wedge mechanism adapted to move the latch and then the wedge mechanism into latching position.

In testimony whereof I have hereunto subscribed my name in the presence of two subscribing witnesses.

BAYARD E. TAYLOR.
